UNITED STATES PATENT OFFICE.

AUGUST WEBER, OF LAWRENCE, KANSAS.

PIANO PLATE AND SOUNDING BOARD.

Application filed July 5, 1924. Serial No. 724,278.

This invention relates to pianos, and more particularly to the plate and sounding board therefor.

It is an object of this invention to provide a plate and sounding board for pianos that will produce, with and through the scale, a tone of greater power and quality than has heretofore been obtainable from pianos such as are now being manufactured.

10 It is a further object of the invention to provide a heavier and stronger plate for the scale which is also formed with an additional treble bar or support to eliminate the tendency to weaken or give.

15 An even further object of this invention is the provision of a convexo-concave sounding board to be used in conjunction with the above-mentioned plate, and which is braced and held in shape by a plurality of ribs, 20 spaced in a special manner and extending angularly across the back of said sounding board and so formed to hold the desired convexity within said board.

With these and other objects in view, 25 which will become more apparent in the following description and disclosures in the drawings, the invention comprises the novel features of construction hereinafter described and more particularly pointed out 30 in the appended claims.

In the accompanying drawings which illustrate a preferred embodiment of the invention, and in which similar reference characters refer to like parts throughout the 35 several views,—

Figure 1 is a face view of a piano plate positioned in front of the sounding board and having most of the strings removed for clearness.

40 Figure 2 is a central horizontal section through the plate and sounding board taken on line II—II, showing, in an exaggerated way, the convex face of the sounding board.

45 Figure 3 is a rear elevation of the sounding board embodying the invention, showing the braces and new method of spacing the same.

Figure 4 is a fragmentary, vertical sectional view taken on line IV—IV of Fig. 50 1, looking in the direction of the arrow.

For the purpose of illustrating and explaining the operation of the invention, I have shown the same incorporated in an upright piano, but it must be understood that 55 the invention may be used in any piano

using a plate with a sounding board located adjacent thereto.

Referring now to the drawings, and more particularly to that portion illustrating the sounding board 5 which is formed with a 60 convex face and made approximately twice as thick at the center than at its periphery, as clearly shown in Figs. 2 and 4. The thickness of the board tapers gradually from the center to the edges. 65

Sounding board 5 has a flat border 6 extending entirely around the edge that is used in securing the board to main casing 7 of the piano. A plurality of ribs 8 arranged in parallel relation and at an angle of approximately 45 degrees, serve as braces to maintain the convexity of sounding board 5. These braces 8 are spaced at varying distances from each other, as shown in Fig. 3, to correspond with the stringing arrangement on the plate. Those braces 8 located behind the treble scale are closer together than the ones behind the bass and longer center scale strings. This distance is of 70

great importance and varies from substantially five inches at the bass corner to two inches at the opposite or treble corner. Mute braces 8 extending at right angles to braces 8, are also arranged with special regard to 75 the stringing. A sounding board constructed in accordance with this invention, possesses the power to remain in shape after the pressure is exerted on the bridges 9 and 10, and after once set produces a tone of 80

larger resonance and higher quality than has heretofore been possible. Weather conditions and constant string pressure will have no effect on the sounding board and, obviously, the instrument will remain in 85 better tune.

In placing the sounding board 5 in the piano, an initial convexity of approximately two and one-half inches is established and the pressure due to stringing allowed to force the same back to substantially one and three-fourths inches. Further dishing-back during the life of the piano is thereby eliminated. 90

Plate 11 may be made with extra heavy cross bars 12 and 13 to strengthen the same. 105 A support 14 connecting the large gap near the treble scale produces a desired rigidity, and eliminates the possibility of breaking. A tapering bar 15 also is added to strengthen the plate. 110

Bars 12, 13 and 15 constitute the "breaks" in stringing around which the majority of faulty notes are found in pianos now on the market. A new division, formed by these 5 bars, and the varying string lengths, together with the combinational use of plate 11 and sounding board 5, produces a result not before attained. The string number with their locations are as follows:

- 10 12 single bass strings.
- 32 double bass strings.
- 96 center register strings.
- 84 treble strings.

I claim:

- 15 1. In combination, in a piano plate and sounding board assembly, a plurality of single bass, double bass, center register and treble strings carried by said plate, a convexo-concave sounding board positioned adjacent said plate having bridges on the convex face thereof in contact with said strings and a plurality of braces rigidly secured to the concave back, disposed at an angle to the sides thereof and parallel to each other,
- 20 23 the distance apart of said braces gradually decreasing from the location behind said plurality of single bass strings as the location behind said plurality of treble strings is approached.
- 25 30 35 2. In combination, in a piano plate and sounding board assembly, a plurality of single bass, double bass, center register and treble strings respectively carried by said plate, a convexo-concave sounding board positioned adjacent said plate having bridges on the convex face thereof in contact with

said strings, means for securing said plate to the edge of said board and a plurality of braces rigidly secured to the concave back, said plurality of braces including a pair of 40 parallel mute braces crossing a portion of said board from one edge to another adjacent diagonally opposite corners thereof and a series of parallel braces rigid to and extending across the concave back between said 45 mute braces and at right angles thereto, said series of braces being wider apart at the location behind the plurality of single bass strings and gradually decreasing in distance apart as the location behind said plurality of 50 treble strings is approached.

3. A piano sounding board comprising a tapering convexo-concave board having its thickest portion at the center of convexity, a plurality of parallel braces across the back 55 of said board and conforming to the contour thereof, the distance between said braces varying in accordance with the tone vibrations of the scale behind which they are positioned.

4. A piano sounding board comprising a convexo-concave board having its convex surface adjacent to and facing the plate and scale of the piano and a plurality of parallel braces across the back of said board with 60 the distance between said braces varied in accordance with the tone vibrations of the scale behind which they are positioned.

In testimony whereof I hereunto set my signature this 2nd day of July, 1924.

AUGUST WEBER.
